UNITED STATES PATENT OFFICE.

CHARLES HENRY PALMER AND JOHN WILLIAM DENMEAD, OF AKRON, OHIO.

STRIP PRINTING AND PERFORATING MACHINE.

SPECIFICATION forming part of Letters Patent No. 589,570, dated September 7, 1897.

Application filed April 8, 1897. Serial No. 631,263. (No model.)

To all whom it may concern:

Be it known that we, CHARLES HENRY PALMER and JOHN WILLIAM DENMEAD, citizens of the United States, residing at Akron, in the county of Summit and State of Ohio, have invented certain new and useful Improvements in Strip Printing and Perforating Machines; and we do hereby declare the following to be a description of the invention, such as will enable others skilled in the art to which it appertains to make and use the same, reference being had to the accompanying drawings.

Our invention relates to that class of printing machinery that receives the paper or card in the form of a narrow strip or ribbon and perforates the same by one or more indentures at predetermined points in its length, from which it passes over a friction-roller, that is provided with means of lateral adjustment for changing the location of the indentures in the strip of paper or cardboard material with relation to the printing-type that may be in use upon the printing-roller, upon which strip is to be printed in colors any desired matter for labels or boxes for which the same is used.

The object of our invention is to simplify the construction and increase the efficiency and perfection of operation of a machine designed for this purpose.

Our invention contemplates the embodiment of these improvements in a machine which may be used separately or combined with perforating or box-making machinery that will receive the perforated printed paper as it is fed forward in a continuous band in regular lengths for the formation of the box or label, which latter combined machine will form the subject of another application filed simultaneously herewith, Serial No. 632,791, filed April 19, 1897, for a box-making machine.

We do not claim to be the original inventors of the printing and inking or roller features of the machine, but confine ourselves more especially to the mechanism shown in the devices for perforating and feeding the material to secure the printing thereon at desired points between the perforations or spaces, from which is subsequently to be formed boxes or labels, and our devices enable us to feed forward at a rapid rate in a continuous band

the material and insure the proper location thereon of the printed matter in various colors and the correct registry or automatic delivery in the continuous rapid movement of the material therethrough without any liability of displacement or misprint of the same.

The accompanying drawings represent the automatic perforating device that moves forward with the material and the adjustable perforator and means of adjusting the material to regulate the location of the perforation with relation to the printing-roller and the design thereon. This perforation, as before stated, may be a single aperture in the center of the width of the paper or cardboard, or one on each side, for the mere purpose of feeding forward to insure the relative placing of the print or provide the means of adjustment of the position of the design or printed matter upon the material in relation to its position in the formation of boxes, as shown in said application, Serial No. 632,791, or it may be a series of indentures or perforations for the purpose of feeding it forward in proper adjustment and which at the same time will serve the purpose of facilitating the preparation of the parts when used as labels or otherwise.

In the drawings, Figure 1 is a sectional side elevation; Fig. 2, a plan view of the perforating device; Fig. 3, a sectional side elevation of same; Fig. 4, a modification of the perforating-die.

In the drawings, A represents the main supporting-frame, secured on the table by bolts A².

B is the horizontally-reciprocating perforating-die lever; B', the perforating-arm; B², its adjustable perforating-die; B³, the lever crank-pin.

B⁶ is a modification of the perforating-die; b, the die-adjusting slot; b', die-securing bolt; b², lever-bolt; b³, the lever-bolt securing-trunnion forming a part of the reciprocating die-plate b⁴; b⁵, the die-guiding plate.

C represents the die, secured in the reciprocating die-plate b⁴; C', the die-opening; D, the adjustable feed-regulating roller; D', its securing-frame; D², its adjusting-rod held in its supporting-frame D³ by means of bolts D⁴, fastened to the table; d' d², adjusting thumb-screws; d, adjusting screw-thread;

d^3 , shield guide-spring; d^4 , its securing-bolt; E, the die-actuating crank-wheel; E', its supporting-arm secured to the main frame. F is the guiding-roll; G, the feeding and pressure cylinder; G', its elastically-faced surface; II, the printing-roll; II', its type printing-face.

J represents the paper or cardboard material which is being operated on; J', the perforation made in the strip; J², the strip pressure-spring.

In operation the material to be acted upon enters the machine at the surface of the table beneath the reciprocating die and passes over the adjusting wheel or roller D under the shield-spring d^3 , thence over the guiding-roll F to the feeding pressure-cylinder G, that is provided with an elastic surface G', which carries it beneath the roller II, pressing it against its type printing-face II'. From thence it passes outwardly through guide-rolls to any desired point.

The various inking-rolls (not lettered) do not form a part of this application.

As the material passes beneath the reciprocating perforating-die, which is actuated by means of its crank B³, secured to the wheel E, its reciprocating vibratory arm is caused to vibrate on its trunnion-bolt b², and its perforating-die will perforate the material and at the same time move forward in unison with the movement of the paper. The revolution of the crank-wheel E is timed by its gearing connection with its actuating-wheel on the roller-shaft F and causes the perforating-lever, with its reciprocating die-plate b⁴, to move forward when its die is within the aperture in the paper, and as the crank-pin rises in its revolution the die is withdrawn from the paper and its arm B will move back with the reciprocating die-plate without interfering with the forward movement of the material as it is advanced forward by the rollers in passing through the machine.

In order to change the location of the perforations, the feed-regulating roller D is moved backward or forward by means of its thumb-screws d^2 d^2 .

Several printing-cylinders may be provided in the use of different colors or designs, and the accurate registry or placement of the paper for printing thereon at the desired point is insured by the use of our invention, and the material as thus prepared may be fed onward to the box-making machine, as heretofore stated, or wound upon large spools or coils to be used for any purpose desired.

By changing the form of the die labels

known as "tags" may be formed from the material as it passes onward in the usual manner.

Having thus described our invention, what we claim, and desire to secure by Letters Patent, is—

1. In a strip printing and perforating machine, a horizontally-reciprocating die B², secured to its actuating-lever B, means for actuating the lever to cause the die to perforate the strip and move forward therewith during the operation of perforating and to rise and reciprocate back to make a new perforation as the strip is advanced in a continuous movement substantially as shown and described.

2. In a strip printing and perforating machine a horizontally-reciprocating perforating-die combined with an adjustable regulating guide-roll and the printing-rolls whereby the perforations may be varied or changed to secure proper relation of the same to the printing-rolls and the design thereon substantially as shown and described.

3. The combination with the printing-cylinder and its adjustable roll D and guiding-roll F of a reciprocating arm and its vertically-adjustable perforating-die B' pivoted thereon to perforate the material as it moves forward to the printing-cylinder substantially as shown and described.

4. In a printing-machine the combination of the reciprocating die, its vibrating and actuating arm B, the guiding-roll D and adjusting-rod D², the guide-roll F, the feeding pressure-cylinder G and elastically-faced surface G', with the printing-roll H and its type printing-face II' operating substantially as shown and described.

5. The horizontally-reciprocating perforating-die adjustably secured to its actuating-lever B operating on a continuously-moving material for the purpose of perforating the same as it moves forward in combination with the shield guide-spring d^3 , the horizontally-adjustable guide-roll D the frame D' its adjusting-rod D² in the supporting-frame D³ and adjusting thumb-screws d^2 d^2 .

In testimony whereof we affix our signatures in presence of two witnesses.

CHARLES HENRY PALMER.
JOHN WILLIAM DENMEAD.
